FURNITURE

Jules P. Kiesecker, New York, N. Y.

Application July 7, 1934, Serial No. 734,100

10 Claims. (Cl. 5—37)

This invention relates to improvements in furniture and more particularly to the construction of that type of furniture which provides a couch during the day convertible for use as a bed whenever desired.

It is an object of this invention to construct a piece of furniture of the type above described and customarily referred to as a studio couch which is of simple construction and is convertible from a seat into a bed with but little effort and can be made up as a single bed in the morning and used as a couch during the day or can be converted into a double bed by letting down the back.

With these and other objects in view reference is made to the accompanying sheets of drawings illustrating a preferred embodiment of this invention, with the understanding that minor changes may be made without departing from the scope thereof.

In the drawings—

Figure 1 is a view in perspective of a preferred form of this invention when in position to be used as a couch.

Figure 2 is a view in elevation of one end of Figure 1 with the arm removed and parts broken away.

Figure 3 is a fragmentary view in rear elevation.

Figure 4 is a view similar to Figure 2 illustrating the position assumed by the parts when used as a bed.

Figure 5 is a fragmentary view in front elevation of Figure 1 with parts constricted and parts broken away.

The embodiment of this invention, as illustrated, includes a boxlike seat 1 supporting arms 2, preferably not as deep as the seat, on each side thereof and a horizontal back 3.

The boxlike seat 1 is preferably formed upon a framework of metal shapes, preferably channel irons with their flanges extending outwardly, bent in the form of flat arches, with the portions 4 curving from the flat parts 5 forming the ends of the box continued to interlock with similar continuations from the portions 6, curving from the flat portions 7 and 7a forming the front and back, respectively, of the box, to form legs of the frame at the respective corners of the box frame. The respective feet of the legs so formed rest upon and are secured to the corner of a rectangular bottom frame preferably constructed of wood end members 8 connected to front and rear members 9 and 9a, respectively. The under side of the bottom

frame is preferably covered with a closure 10 of thin metal or wood which supports ball bearing casters 11 at each corner so that the couch may be readily moved.

The boxlike seat 1 supports a seat cushion or as shown a plurality of seat cushions 12 preferably upon a plurality of coil springs 13 supported so that their upper coils lie in the same plane with the upper surfaces of the flat arch portions 5 and 7 of the ends and front of the seat frame. Each flat arch portion 5 of each end supports a similar metal skirt 14 depending from the upper sides thereof and extending from front to back of the seat frame. These skirts are preferably formed of sheet metal bent at the top to pass over and embrace the top of the flat arch portion 5 and be secured thereto with the bottom bent back upon itself on the inner side to form a channel portion 15 spaced apart from the flat arch channel 5, as shown in Figure 5. The coil springs 13 are preferably arranged in parallel rows with the bottom coil mounted upon and supported by longitudinal bars or slats 16 in the form of vertical metal strips bent upward at each end 25 and twisted so that the extremity rests upon the upper side of the channel 15 of the end skirt 14 and may be secured thereto. It is preferable to provide equally spaced apart intermediate supports 17 to prevent the seat from sagging. As shown these supports are in the form of metallic flat arches similar to those forming the ends of the seat frame with the tops of the flat arches in alignment with the tops of the channel portions 15 of the ends and 30 the metallic slats 16 are twisted and bent to pass thereover and be intermediately supported thereby, as shown in Figure 5. It is also preferable to provide the wooden bottom frame with cross pieces 17a under each intermediate support. It is preferable to construct the back flat arch member 7a of the seat frame to lie in the same plane as the tops of the intermediate member 17 and in any event below the top of the front member 7, so that the rear of the seat 40 cushions will be resiliently supported by the adjacent row of springs 13. The flat arch members 7 and 7a form the front and back of the seat frame and each member supports depending metallic skirts 18 and 19 in the same manner 50 as the ends support the skirts 14. The front and back skirts 18 and 19 extend from end to end and the bottom of each is provided with an inturned flange 20 lying in the same plane with the bottoms of the end skirts 14. The ends of 55

the seat frame may be provided with a metallic or fabric closure, but it is preferable to form the front with a fabric closure 21 preferably secured to the under side of a wooden strip 22 secured to the under side of the flat arch portion 7, passed thereabout and extended under the bottom of the seat frame and secured to the bottom closure 10 by detachable fasteners 21a, for a purpose hereinafter described.

10 A rectangular metal frame 23 is rotatably mounted upon the seat frame by hinges 24 secured to the bottom of frame 23 and to the skirt 19 of the rear member 1a of the seat frame. A frame 25, preferably of wood, coextensive with the back of the couch for supporting the back cushions 26 is slidably mounted upon the forward side of the metal frame by a plurality of guide rods 27 secured at one end to the upper parts of the sliding frame 25 with the lower portions passing through the top of the metal frame 23 to be received within guide sleeves 28 mounted upon the hinged metal frame 23, and having metal guide clips 29 secured to the bottom of the sliding frame 25 adapted to slidably embrace the guide sleeves 28 to provide aligned reciprocation of the sliding frame 25 upon the hinged frame 23.

As shown in Figure 1, the rear cushions 26 are supported at an angle to seat cushion 12 with their lower ends overlapping the seat cushions, as shown in Figure 2. To accomplish this a metal plate 30 is secured to each end of the sliding frame 25 with its rear edge parallel thereto and its bottom extending at right angles 35 to the rear edge to overlap the seat cushions 12. The front edge is formed on the desired angle and is provided with means to support the back cushion 26. The apex of the plates 30 formed by the meeting of the bottom and front edges 40 are each provided with a guiding and supporting roller 31 mounted thereon to travel over a track 32 formed on a plate 33 secured to each end of the seat frame, as by securing the plate to the end skirt 14. The track 32 is so proportioned that the rear seat cushions 26 will be 45 supported by the sliding frame 25 with their lower ends overlapping the seat cushion 12 and the base of the side plate 30 are so proportioned when the hinged frame 23 is rotated rearwardly 50 to bring the front edges of the plate 30 in a horizontal plane, the rear cushion 26 will be supported in the plane of the seat cushion 12 and during this movement the tracks 33 cause the cushions to clear each other. The end plates 55 30 are preferably provided with inturned flanges 34 along the angular edges to which are secured a plurality of coil springs 35 secured at their other ends to a woven wire cushion support 36. The rear cushions 26 are held upon their support 60 as by providing wooden cross pieces 37 along the top of the sliding frame 25 to which the fabric of the top of the cushion may be attached.

The back is secured in its normal or upright position by slip bolts 38 on each end 30 removably engaging sockets 39 therefor mounted upon the guide plates 33 secured to the ends of the seat frame or by any other equivalent means. A pair of link motion legs are provided at the back of the hinged frame 23 adjacent each end 65 70 with one link 40 hinged at one end to the top of the hinged motion frame 23 and preferably mount a ball bearing roller 41 at the other end, with the link 42 hinged at one end to the lower part of the sliding frame 25 with the other end 75 in sliding engagement with the link 40. The

link motion legs are so proportioned that when the back is in its normal upright position the links 40 and 42 fold up against the back, and when the back is released and rotated rearwardly, the links slide over each other and are provided with a limiting means to form a support for the back when the cushions of the back lie in the plane of the cushions of the seat.

The ends 2 are preferably spaced apart from each side of the seat frame and rest upon the 10 bottom closure 10 of said frame and are attached by braces or brackets 43 secured to the end skirts 14. It is also preferable to construct the ends 2 in the form of boxes open at the top and provided with upholstered hinged closures 44 15 forming arms or head rests.

The seat portion may be readily made up as a single bed by lifting the sliding frame and a couch cover thrown thereover, if desired, so as to be usable as a couch during the day. The 20 space within the hollow arms 2 below the hinged arms 44 and the space between the spring slats 18 and bottom closure 10 covered by the detachable front curtain 21 provides storage space for sheets, blankets, pillows, etc., when the bed 25 is unmade.

By releasing the slip bolts 38 the back is readily moved into the longitudinal position to form a double bed and as both the seat frame and back supporting legs are mounted on ball 30 bearing casters the piece of furniture is easily moved about upon the floor.

What I claim is:

1. A studio couch including a boxlike seat having a metallic frame and a cushion mattress 35 resting upon springs supported upon said frame and an expandible back hinged to said frame having a cushion mattress secured along the upper edge of one of the expandible members in combination with means for supporting the 40 upper surfaces of the said cushion mattresses in the same horizontal plane upon movement of the back in one direction and means upon movement of the back in the opposite direction to carry the end of the back mattress over the 45 adjacent end of the seat mattress to overlap the top thereof and support the back mattress at an angle thereto with the back in a vertical position, wherein one member of the expandible back is hinged to the rear of the seat, below 50 the top of the front, and wherein the other member of the expandible back is provided with angular sides supporting the back mattress.

2. The structure of claim 1 wherein the expandible back includes one member hinged to 55 the frame reciprocably mounting the cushion mattress carrying member.

3. The structure of claim 1 wherein the expandible back includes one member hinged to the frame reciprocably mounting the cushion 60 mattress carrying member and means upon the reciprocable member adapted to coact with means upon the frame to releasibly hold the back when rotated to a vertical position.

4. The structure of claim 1 wherein the expandible back includes one member hinged to the frame reciprocably mounting the cushion mattress carrying member and wherein said means for supporting the mattresses in the same plane includes a pair of legs, one pivoted to the 70 hinged member and the other pivoted to the reciprocable member of the back and the free ends having a sliding contact with each other and provided with means to lock the free ends when extended and allow the legs to fold one 75

on the other when the back is moved to a vertical position.

5. The structure of claim 1 wherein the expandible back includes one member hinged to the frame reciprocably mounting the cushion mattress carrying member, and wherein the means for carrying the back mattress over the seat mattress includes means upon the reciprocable member of the back coacting with means 10 upon the ends of the seat frame.

6. The structure of claim 1 wherein the expandible back includes one member hinged to the frame reciprocably mounting the cushion mattress carrying member by providing the 15 hinged member with a plurality of guides coacting with guides upon the reciprocable member.

7. A studio couch including a boxlike seat frame formed of a plurality of structural metal shapes bent in the form of flat arches with angular legs depending therefrom and having the 20 said legs adjacent the corners interlocked with the flat arch members forming the ends each supporting a metallic end member formed at 25 its lower edge into a transverse structural metal shape, with the flat arch member forming the rear of the seat in line with said transverse shape supporting a metallic rear member, and a

back frame pivoted at its lower edges to said metallic rear member slidably mounting a cushion mattress carrier for reciprocation in the direction of the hinged edge.

8. The structure of claim 7 wherein a plurality of parallel slats are mounted upon said transverse shapes supporting a plurality of springs with their tops in line with the front and ends 5 of the seat frame.

9. The structure of claim 7 wherein the ends 10 of the sliding carrier mount triangular metal plates of greatest width adjacent the seat frame with a spring fabric secured to the edges of the plates most distant from the carrier.

10. The structure of claim 7 wherein a plurality of parallel slats are mounted upon said transverse shapes supporting a plurality of springs with their tops in line with the front 15 and ends of the seat frame and wherein the ends of the sliding carrier mount triangular metal plates of greatest width adjacent the seat 20 frame with a spring fabric secured to the edges of the plates most distant from the carrier adapted upon rotation of the hinged back to position the spring fabric in the same plane with 25 the tops of the springs of the seat frame.
